P. J. TIMBERLAKE

GARMENT STRETCHER

Filed Jan. 8, 1923

Fig. 2.

Inventor,
Paul J. Timberlake.

By *John S. Parker*
Attorney

UNITED STATES PATENT OFFICE.

PAUL J. TIMBERLAKE, OF JACKSON, MICHIGAN.

GARMENT STRETCHER.

Application filed January 8, 1923. Serial No. 611,484.

To all whom it may concern:

Be it known that I, PAUL J. TIMBERLAKE, a citizen of the United States, residing at Jackson, in the county of Jackson and State 5 of Michigan, have invented certain new and useful Improvements in Garment Stretchers, of which the following is a specification.

My invention relates to foldable frames over which garments such as infants' shirts 10 may be drawn after being laundered, and on which they remain in stretched condition while drying. In Patent 877,226 issued to me January 21, 1908 is shown a garment stretcher having many features in common 15 with the one herein to be described as embodying my present invention, which invention has for its object to improve garment stretchers in order to simplify them, reduce the cost of manufacture, and also reduce the 20 danger of the enamel, with which the wires of which the frame parts are formed are coated, from being chipped or marred in the assembly of the parts and their subsequent manipulation as the article is used.

25 In the accompanying drawings—

Figure 1 is an elevation of a garment stretcher embodying my present invention; and Figs. 2 and 3 show frames, in elevation, embodying different forms of the invention.

30 Referring to such drawings 2 indicates the central frame, this being the part over which the body of the garment is stretched. This frame part comprises side bars 3, 3 and a top bar 4, the latter being preferably 35 formed of the inturned ends of the wire of which the frame is formed, which are united as by twisting, one of the wires being longer than the other and formed into a suspending hook 5. Each side bar 3 is formed near its 40 upper end with eyes or loops 6, 6, spaced apart at such distance as to suit the size of the lateral or sleeve frames 9, 9 which are pivotally connected with the central frame 2.

45 In each pair of loops 6 is supported a small tube 7, formed preferably of metal and with its ends expanded, as at 8, to properly hold it in place in loops 6, as represented in the drawing. The sleeve frames 50 9 are each formed of a single piece of metal bent into open or loop form with inturned ends 10 which are inserted into the hollow cylinders 7, in which they are free to turn. The resiliency of the wire of which the 55 frames 9 are formed will be sufficient to hold the ends 10 of the sleeve frames in place.

The sleeve frames may be turned inward as indicated in dotted lines in the drawing, folding one behind and the other in front of the central frame 2. When thus folded 60 the frame occupies but little space and may be conveniently packed or stored. When in use the sleeve frames are opened out as represented in full lines in the drawing.

It will be understood that the wires constituting the several frames of the article are enameled before they are assembled into the complete article. If there should be any marring of the enamel during the assembly of the parts this almost invariably occurs 70 on the inturned ends of the sleeve frames 9, and as they are confined within the cylinders 7 it is not apparent.

The sleeve frames hinge freely in the tubes or cylinders 7 which are of a size to 75 permit free movement without there being undue looseness of the articulating parts.

The loops 6, 6 formed in the side bars 3 of the main frame are directly connected by portions 11 of the side bars, the length of 80 these portions determining the distance between the loops, which loops, it will be understood, should be axially in line with each other.

The construction which I have described 85 and which is illustrated in Fig. 1 is the one which I prefer since it makes the most attractive and substantial article. However, the frames shown in Figs. 2 and 3 embody 90 certain of the novel features which have been described, and are cheaper to manufacture than the article illustrated in Fig. 1. Referring to Fig. 2 it will be seen that the inturned ends 10, 10 of the sleeve frames are supported directly in the loops 6 of the side 95 bars of the central frame and that such ends 10 are united by a ferrule 12.

In the form of invention illustrated in Fig. 3 the inturned ends 10 of the sleeve frames are supported directly in the loops 6 but are 100 not directly connected with each other, being held in place by the resiliency of the frame 9. In this form of the invention a connecting tube into which the inturned ends of the sleeve frame enter, whether that tube be in 105 the form of a ferrule as shown in Fig. 2, or a cylinder like that illustrated in Fig. 1, is dispensed with entirely.

What I claim is:—

1. A garment stretcher comprising a central frame of wire and having side bars formed with eyes or loops which are united

by intermediate portions of the side bars, sleeve frames of open form with inturned ends in line with each other such ends passing through the said eyes or loops in the 5 side bars of the central frame and freely hinging therein.

2. A garment stretcher comprising a central frame of wire and having side bars formed with eyes or loops which are united 10 by intermediate portions of the side bars, sleeve frames of open form with inturned ends in line with each other such ends passing through the said eyes or loops in the side bars of the central frame and freely 15 hinging therein, the inturned ends of the sleeve frames entering and being surrounded by a tube.

3. A garment stretcher comprising a cen-

tral frame having side bars, open ended hollow cylinders supported by the side bars, 20 and sleeve frames of open form with inturned ends in line with each other, such ends being inserted into the opposite ends of the hollow cylinders whereby they have hinge connection with the central frame. 25

4. A garment stretcher formed of wire and comprising a central frame having side bars each of which is shaped to form loops which are spaced apart, small hollow cylinders supported in the said loops and sleeve frames 30 of open construction with inturned ends that are inserted into the opposite open ends of the cylinders and are thus hingedly united with the central frame.

PAUL J. TIMBERLAKE.
